UNITED STATES PATENT OFFICE.

JAMES E. GASTON, OF SPARTA, ILLINOIS, ASSIGNOR TO THE GASTON ELECTRICAL MANUFACTURING COMPANY, OF SAME PLACE.

DESIGN FOR AN ELECTRIC-LAMP FRAME.

SPECIFICATION forming part of Design No. 21,701, dated July 12, 1892.

Application filed June 4, 1892. Serial No. 435,567. Term of patent 14 years.

To all whom it may concern:

Be it known that I, JAMES E. GASTON, of the city of Sparta, Randolph county, and State of Illinois, have invented a certain new and original Design for Electric-Lamp Frames, of which the following is a full, clear, and exact description, reference being had to the accompanying drawings, forming a part hereof.

Figure 1 is a side elevation of an electric-lamp frame embodying my design, and Fig. 2 is an end elevation of the same.

The leading feature of my design consists of a frame having a general rectangular outline with angular terminal projections 1 at its opposite ends and angular vertical portions 2, beyond which said terminal projections 1 extend a considerable distance.

3 indicates a horizontal body portion extending intermediately of the angular projections 1 and connecting the same, and projecting from both front and rear sides of the body 3 is a series of horizontal and parallel projections 4.

Projecting from one face of each of the angular portions 2 at the base thereof and extending each in a direction at right angles to said face are horizontal bodies 5, having substantially-parallel lower and upper surfaces. Rising from the upper surface of each of these bodies 5 and extending upward a considerable distance are two projecting bodies 6, which project from and are connected at

one of their vertical edges to the face of the angular vertical portions 2. The free edges and upper ends of the parts 6 have a curved or 35 irregular outline.

Each of the angular vertical portions 2 has a comparatively large opening 7, of irregular contour, formed therein, and at one side of each of said openings adjacent the upper end 40 thereof is a small opening 8, of circular form.

Adjacent the outer terminal of each of the angular projections 1 and formed therein, is a small opening 9, of irregular form, and in the horizontal body 3, intermediate of the 45 small openings 9 and located in a horizontal line, a series of openings 10, of irregular outline is formed.

An important feature of my design is the oppositely-located horizontal and parallel projections 4, located on opposite sides of the horizontal body portion 3, with the projections on one side of the said body portion in the same plane as the projections upon the opposite side of said body portion. 55

What I claim is—

The design for an electric-lamp frame, as herein shown and described.

In testimony whereof I affix my signature in presence of two witnesses.

JAMES E. GASTON.
